UNITED STATES PATENT OFFICE.

LOUIS N. D. WILLIAMS, OF OGONTZ, PENNSYLVANIA, ASSIGNOR TO SCOTT & WILLIAMS, INCORPORATED, OF NEW YORK, N. Y., A CORPORATION OF MASSACHUSETTS.

DEVICE FOR TRANSFERRING KNITTED FABRICS.

Application filed December 1, 1925. Serial No. 72,484.

This invention relates to devices for transferring knitted fabrics—loop for loop—between different types of machines as required in producing certain articles of manufacture, such for example as stockings and the like. More specifically speaking, the present invention is concerned with transfer devices of the special kind shown and described in my Patent No. 1,348,195 dated August 3, 1920, adapted to receive a stocking from the producing machine for doubling the loops of opposite halves of the tube to close the toe pocket, and intended to be inserted in a sewing machine such as disclosed in my Patent No. 1,315,064 of September 2, 1919 for subsequent uniting of the doubled loops in finishing the stocking.

Transfer devices of the kind referred to were usually constructed with looping points which had to be individually secured, and on account of the great number required, assembling of such devices was not only extremely difficult and tedious, but very expensive. Moreover, on account of the extreme sharpness of the looping points of the fabric engaging instrumentalities heretofore employed, and their liability to bending, considerable difficulty has been experienced in maintaining the points properly spaced, more particularly with regard to assuring correct registry when brought end to end in the act of loop transfer in the manner above briefly explained; disalignment, though ever so slight, providing intervals for the fabric loops to slip through and resulting in so called "drop stitches".

My present invention is directed, in the main, toward overcoming the various difficulties recited, i. e. toward improving such transfers for devices so as to obtain, on the one hand, the advantages of greater structural simplicity particularly with reference to the number of parts required, thereby to render assembling very much easier and less expensive; and on the other hand, to insure against the possibility of stitch dropping notwithstanding slight disalignment or bending of the looping points.

One way in which the foregoing desiderata may be readily attained, will be manifest from the detailed description which follows of the typical embodiment of my invention shown in the drawings, whereof Fig. I, is a side elevation of the transfer device.

Fig. II is a perspective view of one of the 55 fabric loop engaging instrumentalities.

Fig. III is a detail cross section taken as indicated by the arrows III—III in Fig. I.

Figs. IV and V are fragmentary side elevations of the portion of the structure illustrated in Fig. III showing successive steps in assembling.

Fig. VI is a detail sectional view taken as indicated by the arrows VI—VI in Fig. V.

Fig. VII is an illustration showing one of 65 the steps incidental to the formation of the fabric engaging instrumentality depicted in Fig. II; and,

Fig. VIII is a fragmentary view showing an alternate embodiment of my invention. 70

With reference more particularly to Fig. I, the transfer device there depicted comprises component semi-circular shell sections 10, 11, which, when occupying the full line positions, jointly constitute a cylindric holder from one edge of which project the points of the fabric engaging instrumentalities, said points being adapted to receive the fabric loops L from the needles N of a knitting machine as shown in Fig. III. The section 11 is connected to the section 10, by hinges 13, so as to be swingable to the dotted line position for registry and end to end abutment of its points with those of said section 10. When the parts are so positioned, the fabric loops previously received by the section 11 can be displaced therefrom and doubled with loops on the points of the section 10, such transfer being facilitated by aid of stripper segments 15 with which the two sections are respectively equipped. These 75 stripper segments 15 are supported by pins 16 (see Fig. III) appropriately guided for longitudinal shifting in the parts 10, 11, said pins extending from arcuate actuating plates 17 that are engageable from within the device, 80 all as described in the patent to which reference has been made hereinbefore.

As shown in the several illustrations, the cylindric holder jointly constituted by the parts 10, 11 is provided at one end with a circumferential protuberance 18 which is characterized by having a series of equally-spaced peripheral notches 19 that are intersected by a continuous cross groove 20 for anchorage of the web engaging instrumentalities 21 100 (Fig. II) in the manner to be presently explained. In the instance illustrated, these web engaging instrumentalities are made to 105

U-shape configuration and thus afford loop engaging points 22 in duplo. In order to better resist bending, the shanks of said points are preferably fashioned to fluted or channeled cross-section, although joined by a solid connecting portion 23 which is extended laterally to serve as an anchorage projection; while their extremities are merged into tapered tips of solid section with flat terminal ends 24 of substantial lateral surface area. In practice, the point ends 24 may vary from a sixty-fourth to a sixteenth of an inch in diameter according to the gage of the fabric to be transferred. A double pointed fabric engaging instrumentality of this kind may obviously be constructed in a number of different ways, one convenient and preferred method being to employ a blank length of strip material, for example round wire, flattening the opposite ends of such blank, fashioning the flattened portions to the desired channeled cross section, and at the same time providing the tapered point tips. Thereupon the structure of Fig. VII may be converted into the complete double pointed instrumentality 21 of Fig. II—simply by double bending in a manner that is clearly obvious from the illustrations.

In assembling the transfer device, the laterally extending anchorage portions 23 of the web-engaging double-pointed instrumentalities 21 are engaged within the cross groove 20 of the holder element 10, 11, with the immediately adjoining portions of the point shanks 22 similarly lodged in neighboring pairs of peripheral notches 19, all as shown in Fig. IV. With the instrumentalities 21 placed as just described, the contiguous side walls of the slots 19 are swedged over upon the recessed portions as shown at 25 in Figs. V and VI—by hammering or otherwise—to firmly secure them in the holder 10, 11.

When the section 11 of the transfer device is turned over upon the companion section 10—in accordance with the dotted line showing in Fig. I—it will be observed that, by virtue of the dull flat ends 24 of the looping points, abutment between opposing pairs of them obtains over a definite surface area, whereby, notwithstanding slight disalignment after the manner indicated in Fig. V, sufficient surface overlap is assured to preclude the possibility of "stitch dropping" during doubling of the fabric loops for the purpose outlined in one of the introductory paragraphs of this specification.

If desired, and instead of with but two points, the fabric engaging instrumentalities 21 may, within the scope of the appended claims, be made with the points in greater multiple, or in other words, to resemble a comb like structure capable of being secured to the holder 10, 11 in precisely the same manner as already described.

In the alternative construction of Fig.

VIII, the laterally-extending anchorage portions 23 of the fabric engaging instrumentalities 21 are clamped against a flange 26 of the holder element 10, 11 by a plate 27. This plate 27 is accommodated in the cross groove 20 (which in the present instance is considerably larger than in the first embodiment), and its bottom face is indented at the proper intervals, as indicated at 29, to assist in maintaining the desired spacing of the instrumentalities 21. Screws 30 are employed as a convenient means to draw upon the plate 27 after the parts are otherwise assembled; while the side walls of the notches 19 are preferably swedged over upon the point shanks 22 in the manner previously explained. The modified construction just described, it will be seen, enables replacement to be made more readily in the event of the breakage of any of the points, simply by removing the plate 27 and drawing the fabric-engaging instrumentality 21 upward from the notches 19 in which their shanks 22 are lodged.

It is to be understood that my invention is not necessarily confined merely to the construction of transfer devices of the annular or ring form useful with circular knitting machines, but that it may be embodied with equal advantages in the straight type of transfer devices such as ordinarily employed in connection with flat knitting machines. It will also be apparent that the advantages resultant from the use of dull ends will be the same whether the points be in multiple as above described, or single as heretofore.

Having thus described my invention, I claim:

1. A device for transferring knitted fabrics including a holder element having a series of notches intersected by a continuous cross groove; in combination with a fabric loop engaging instrumentality affording a number of spaced points integrally joined transversely by a common connection, the latter being adapted to engage in the cross groove of the holder element, and the immediately adjoining portions of the point shanks to engage in the notches.

2. A device for transferring knitted fabrics including a holder element having a series of notches intersected by a continuous cross groove; in combination with a fabric loop engaging instrumentality affording a number of spaced points integrally joined transversely by a common lateral connection, the latter being adapted to engage in the cross groove of the holder element, and the immediately adjoining portions of the point shanks to engage in the notches.

3. A device for transferring knitted fabrics including a holder element having a series of notches intersected by a continuous cross groove; in combination with a fabric loop engaging instrumentality affording a

number of spaced points integrally joined by a common transverse connection, the latter being adapted to engage in the cross groove of the holder element, and the immediately 5 adjoining portions of the point shanks to engage in the notches, and means to secure the fabric engaging instrumentalities in place.

4. A device for transferring knitted fabrics including a holder element having a series of notches intersected by a continuous cross groove; in combination with a fabric loop engaging instrumentality affording spaced points integrally joined by a common transverse connection, the latter being adapted 10 to occupy the cross groove of the holder element, the immediately adjoining portions of the point shanks to occupy the notches, and said instrumentalities being secured in place through swedging of the side walls of the 15 notches aforesaid over upon them.

5. A device for transferring knitted fabrics including a holder element having a series of vertical notches intersected by a continuous horizontal cross groove; in combination 25 with fabric loop engaging instrumentalities each affording a pair of spaced points integrally joined by a transverse connection, said connection being adapted to engage in the horizontal groove of the holder and the 30 contiguous portions of the point shanks in the vertical notches.

6. A device for transferring knitted fabrics comprising two component members each with projecting instrumentalities having multiple loop-engaging points capable of being brought into registry for transfer of fabric loops between them, said points having dull flat ends for intimate abutment over a substantial surface area to prevent release of 35 the fabric loops incidental to transfer as aforesaid.

7. An annular device for transferring knitted tubular fabrics comprising two component arcuate members hinged together for 45 swinging movement for registry of attached instrumentalities having multiple loop-engaging points projecting respectively from them and doubling of the fabric loops on one set with those on the other set, said points 50 having dull flat ends for intimate abutment over a substantial surface area to prevent release of the fabric loops incidental to transfer as aforesaid.

8. An integrally-formed fabric engaging 55 instrumentality useful in connection with

devices for transferring knit fabrics affording a multiplicity of spaced looping points.

9. An integrally-formed fabric engaging instrumentality useful in connection with devices for transferring knit fabrics affording 60 a multiplicity of spaced looping points and provided with a laterally-extending anchorage projection.

10. A fabric engaging instrumentality useful in connection with devices for transferring 65 knit webs having the form of parallel points each with a dull flat end affording a substantial surface area, for the purpose specified.

11. An integrally-formed fabric engaging 70 instrumentality useful in connection with devices for transferring knit fabrics affording a multiplicity of spaced looping points with dull flat ends.

12. A fabric engaging instrumentality useful in connection with devices for transferring 75 knit fabrics having the form of a **U** thereby to afford loop-engaging points in duple.

13. A fabric engaging instrumentality useful in connection with devices for transferring 80 knit fabrics having the form of a **U** thereby to afford loop-engaging points in duple, and with the connecting portion of the **U** extending laterally to provide an anchorage projection. 85

14. A fabric engaging instrumentality useful in connection with devices for transferring 90 knit fabrics formed integrally from a length of strip material bent to **U**-shape to afford loop-engaging points in duple.

15. A fabric engaging instrumentality useful in connection with devices for transferring 95 knit fabrics formed integrally from a length of strip material bent to **U**-shape to afford loop-engaging points in duple with fluted shanks and solid terminal tips.

16. A fabric engaging instrumentality useful in connection with transfer devices for 100 knit fabrics constructed integrally from a blank with opposite ends fashioned to fluted or channelled cross section merging with solid tapered terminal tips, and the whole bent to **U**-shape configuration to afford loop 105 engaging points in duple.

In testimony whereof, I have hereunto signed my name at Philadelphia, Pennsylvania, this 28th day of November, 1925.

LOUIS N. D. WILLIAMS.
